FILM CARTON WITH MAILING TAG

Bruno C. Roehrl, Binghamton, N. Y., assignor to
General Aniline & Film Corporation, New York,
N. Y., a corporation of Delaware

Application March 10, 1942, Serial No. 434,097

4 Claims. (Cl. 229—37)

My invention relates to containers or cartons and while susceptible to many uses and manufacture in many sizes and shapes, I will hereinafter describe it with relation to its uses for the packaging of films and the like.

In the film industry, it is the present practice of manufacturers to enclose their films for sale in individual attractively decorated containers or cartons. These cartons are, ordinarily of a single thickness of a light grade of cardboard and to the outer surface of the carton is applied advertising matter, trade marks, and data indicating the size and type of the film. After the film has been removed, the carton is usually discarded as being of no further use.

In view of the increasing practice among film users to return their exposed films, by mail, to the manufacturer or to some reputable processor for development, the present carton, although carrying the customary advertising matter and other indicia, is also provided with sufficient space for mailing data or addresses and further, when ready for mailing to the processor is sufficiently reinforced to withstand the usual hazards to which it may be exposed while en route.

Accordingly, it is one of the objects of this invention to provide a carton of such simplicity as to impose no material increase in the cost of its manufacture.

A further object of the invention is to provide a container or box of the above character which will be strong and durable and well-adapted to withstand mailing without injury to the contents.

A further object is to provide a box or container of the above character which may be inexpensively manufactured and assembled and re-used without material difficulty.

A further object is to provide a box of the above character provided with interfitting and interlocking sealing and closing tabs, adapted to hold the parts in closed position during mailing.

Further and additional objects of my invention will become apparent from the following description:

In the accompanying drawing forming a part of this application and illustrating one of various possible embodiments, like numerals are employed to designate corresponding parts throughout the same. In this drawing,

Fig. 1 is a plan view of a blank from which a conventional container is fabricated together with the added feature of the present invention;

Fig. 2 is a perspective view of the box in one position as sold;

Fig. 3 is a similar view of the box partly opened; and

Fig. 4 is a similar view of the box partly refolded for return mailing.

5. Fig. 5 is a similar view of the box refolded for return mailing and illustrating how the end tabs are inserted.

Referring now to the drawing in detail, and more particularly to Fig. 1 illustrating the complete blank from which the box or container is made, 1, 2, 3, and 4 are the conventional four side panels used in making a rectangular box. The longitudinal side of the first panel is provided with a sealing flap 1a which, when the blank is folded into a rectangle, is secured to the inside of the adjacent longitudinal edge of the panel 4, thus making the box. Each one of these panels 1, 2, 3, and 4 is provided with the usual sealing and closing interfitting and interlocking end flaps and indicated at 1a, 1b, 2a, 2b, 3a and 4b and these are assembled in conventional way and sealed as and where necessary.

Adjacent the side panels 1 to 4 are a second series of panels 5, 6, 7 and 8 which are folded 25 back and forth upon themselves, as shown in Figs. 2 and 3, and the end panel 8 is provided with two end closures or tabs 8a and 8b which, as shown in Figs. 1 and 5, are adapted to be inserted beneath the top end flap extending from the first- 30 mentioned panels, in the manner shown. These end flaps 8a and 8b are so shaped as to permit a snug interlocking fit with the other end closure flaps whereby when the parts are assembled they can only be removed with difficulty, thereby being well-adaptable to withstanding the stresses 35 and strains of mailing.

It is, of course, to be understood that the invention is not limited to the particular embodiment shown in the accompanying drawing. Instead of a series of four panels 5, 6, 7, 8 adjacent to side panels 1 to 4, it is possible, for instance, to have merely two panels, 5 and 6, constituting a loose return mailing flap on which may be written the addresses of sender and sendee. Furthermore, end panels 6 and 7 or 1 and 8 may be torn from each other so that, although the box is sold in the form as shown in Fig. 2 or Fig. 5, panels 7 and 8 or panel 8 may be detached and the remaining panels then constituting a loose 50 return mailing flap.

The box as sold is preferably in the form as shown in Fig. 2 but may also be sold in the form as shown in Fig. 5. When the film, for example, is to be returned to the processor for development, then the end flaps 8a and 8b are removed

from the top closure end shown in Fig. 2 and the panels 5, 6, 7, and 8 are stretched out as shown in Fig. 3 and then wrapped around the box as shown in Fig. 4, whereupon the end tabs 8a and 8b are inserted beneath the top end closure of the main part of the box as shown in Fig. 5.

One of the additional panels, for example, end panel 8, is provided with mailing data spaces, the outer or exposed side of this panel to have the notation "To" up in the corner beneath which the proper address may be inserted on the spaced lines. Similarly, the outer side of another panel is provided to receive mailing data and the word "From" appears in the corner to carry the name of the addressee. Whereupon, when the box is received, the addressee will have the name and address of the party to whom the developed films or prints are to be delivered.

While the invention is herein described as being particularly applicable to film boxes of the conventional four-sided shape, it is clear that, without modification, five or six-sided boxes could be made without departing from the invention, the only point being that if a different number of sides are used in making up the box, then a corresponding number of extra panels to the blank would also be provided, thereby to completely surround the box, as shown in Fig. 4 of the drawing. This extra wrapper around the main body of the box protects the film in transit.

It is thus seen that the present invention is directed to a simple and practical container which may be inexpensively manufactured and assembled and provide a box well-adapted to withstand the hard wear to which it may be subjected without injury to the contents of the box.

Having now particularly described my invention, what I claim as new is:

1. A one piece blank of sheet material comprising a section adapted to be folded in a conventional manner into the form of a rectangular box, said section having a plurality of panels forming the side walls of the box and necessary

end closure and sealing flaps, the end closure flaps being attached to the first and third panels respectively, a second section extending longitudinally of the first named section and having a plurality of panels corresponding in number to those of the first named section, the panels of the sections corresponding in width in sequence beginning with the initial panel of each section of the blank, the panels of the second section being foldable to envelop the side walls of said first named section when the latter is folded in the form of a box, the last panel of the second section having at least one laterally extending flap shaped to snugly fit beneath the end closure flaps of the first named section when the latter is folded in box form.

2. A container formed from a blank of sheet material defined in claim 1.

3. A one piece blank of sheet material comprising a section adapted to be folded in a conventional manner into the form of a rectangular box, said section having a plurality of panels of equal width forming the side walls of the box and necessary end closure and sealing flaps, the end closure flaps being attached to the first and third panels respectively, a second section extending longitudinally of the first named section and having a plurality of panels corresponding in number and width to those of the first named section, the panels of the second section being foldable either back and forth over themselves to lie closely adjacent one side wall or to envelop the side walls of said first mentioned section when the latter is folded in the form of a box, the last panel of the second section having at least one laterally extending flap shaped to snugly fit beneath the end closure flaps of the first named section when the latter is folded in box form.

4. A container formed from a blank of sheet material defined in claim 3.

BRUNO C. ROEHRL.
